JOHANN KRANNICHELD, OF COLOGNE-NIEHL-ON-THE-RHINE, GERMANY.

ELECTRIC IGNITER.

1,263,256.

Specification of Letters Patent. Patented Apr. 16, 1918.

Application filed June 20, 1914. Serial No. 846,351.

To all whom it may concern:

Be it known that I, JOHANN KRANNICHELD, a subject of the King of Prussia, residing at Cologne-Niehl-on-the-Rhine, in the 5 Kingdom of Prussia and German Empire, have invented new and useful Improvements in Electric Igniters, of which the following is a specification.

The present invention relates to an improved electric igniter, which has several advantages over existing devices of the kind.

On the accompanying drawing, which illustrates the invention by way of example, several constructions of the igniter are 15 shown.

Figures 1 and 2 show in longitudinal section one construction in which the insulator carrying the igniting wire is fastened in the tube containing the explosive by a short 20 sleeve in combination with a sulfur casting or the like.

Figs. 3 and 4 represent an igniter in which the insulator is held by a collar.

Fig. 5 shows a similar igniter to that 25 shown in Figs. 3 and 4, but the explosive plug closing one end of the tube containing the charge has a smaller diameter.

Fig. 6 shows a further modification in 30 regard to the manner of securing the plug in the tube.

Fig. 7 represents the incandescence wire in an inclined position.

Fig. 8 is a view corresponding to Fig. 3, but showing the plug carried by the outside 35 sleeve of the igniter.

Figs. 9 and 10 represent another way of fastening the insulating body which carries the incandescence wire in the sleeve.

Figs. 11, 12 and 13, 14 show further 40 constructions of the device for holding the insulator.

Figs. 15 and 16 show another arrangement of the pole pieces on the insulator.

The insulator *a* (Figs. 1 and 2) has a conducting layer *b*, *c* on each side or surrounding each edge (Figs. 15 and 16) and is cut out at the top so as to present a forked shape, the prongs *d*, *e* of said fork being bridged by the wire *f*, which is in contact with the 45 conductive layer *b* of the prong *d* and with the conductive layer *c* of the prong *e*. The electric current is led to the layers *b* and *c* by the wires *g*, *h*, so that the wire *f* can be rendered incandescent. The insulator *a* is 50 secured in the tube *i* by the sleeve *k*, in which said insulator is fastened by a casting *l* of

sulfur or of some other suitable substance. For the purpose of better securing said insulator *a* in the sleeve *k*, the former can be cut out at *m* and the recess or notch thus 60 formed will be filled out by the casting *l*. The wire *f* is surrounded by a combustive *n* of slowly burning and weakly igniting property, and the top of the tube *i* is closed by the plug *o*, which consists of a combustive 65 of quick burning property.

Any suitable combustives having these properties may be employed, for example, potassium nitrate, charcoal and sulfur, with a suitable binder may be used for the quick 70 burning combustive, and the same ingredients mixed with an inert substance as chalk, clay, etc., may be used for the slow burning combustive.

The igniter shown in Figs. 3 and 4 differs 75 from that shown in Figs. 1 and 2 by the insulator *a* being secured in the tube *i* by a collar *k*, which prevents the cast sulfur *l* from penetrating to the charge *n*. A further difference of this construction consists 80 in the fact that the diameter of the plug *o* is reduced by an intercepted sleeve *q*. This igniter is provided with an outer tube *u* in which it is held by the casting *l*. In this tube *u* the plug *o* can be inserted, as shown 85 in Fig. 8, instead of into the tube *i*.

In Figs. 5 and 6 igniters are shown which only differ from those shown in Figs. 3 and 4 by the fact that in Fig. 5 the plug *o* has a still further reduced diameter and fits into 90 a central hole provided at the end of the tube *i*, while in Fig. 6 the plug *o* has a diameter as large as the interior of the tube *i* and is retained in said sleeve by a flange *r*.

According to Figs. 9 and 10 the insulator 95 is held in the tube *i* by two collars *k'*, *k'*, which are provided with a slot on opposite sides (Fig. 10) into which the insulator fits. When these collars are inserted into the tube *i*, they hold the insulator between 100 them.

Figs. 11 and 12 show two views, at right angles to each other, of an insulator which is provided with a hole, through which a tongue *v* provided on the collar piece *k*³ of 105 semi-circular section passes, said tongue fitting into a hole *w* of a second semi-circular collar piece *k*⁴. By this means both collar pieces *k*³, *k*⁴ are united together and hold the insulator between them.

The construction shown in Figs. 13 and 14 differs from that shown in Figs. 11 and

12 only by the fact that the tongue does not fit into a hole in the other collar piece, but fits into a groove *w'* in said other collar piece. The advantage of this construction 5 over that shown in Figs. 11 and 12 consists in the fact that the collar pieces with tongue and groove can be made in long strips from which the separate pieces are cut, it only being necessary to cut off the ends of the 10 tongue, so as to fit into the hole in the insulator.

15 Igniters of the kind above described have, firstly, the advantage that the igniting wire *f*, owing to the fork shape of the end of the insulator *a*, provided with a conductive layer *b, c* on each side, has a considerable length, and is, accordingly, more effective, because the heat conducted away by the metal layers forming the poles is less detrimental. Moreover 20 the length of said wire is quite uniform, because the distance between the prongs *d, e* is always the same. The described manner of attaching the igniting wire has the further advantage that in constructing the igniters the insulators *a* may be fastened in a suitable device with their top ends close together, whereupon the wire *f* can be attached with but extremely little waste to the conductive layers *b, c*. In order to still further 25 increase the length of the wire *f* the prongs *d, e* may be of different length, so that the wire *f* takes an inclined position, as shown in Fig. 7. A further important advantage of this igniter consists in the ability of obtaining a combined or aggregate operation 30 of any number of such igniters electrically connected in series, although constructed for practically momentary ignition. This result is obtained by using the slowly burning charge *n* in combination with the plug *o* of a quick burning character. When the charge *n* has been ignited by the incandescence 35 of the wire *f*, the plug *o* serves at first to isolate the combustion, thus to prevent said combustion from extending to the explosive *s* (Fig. 1), until said plug is itself ignited, whereupon a flame is produced and caused to act on the charge *s*, which is contained in a tube *t* adapted to be pushed over 40 the tube *i*.

What I claim and desire to secure by Letters Patent of the United States is:—

1. An electric igniter comprising in combination a flat insulating body cut out to form a fork shaped end, a layer of electrically conducting material on each side of said body and the prongs of the fork shaped end and on each face of said body, and forming poles. 5

2. An electric igniter comprising in combination an insulating body cut out to form a fork shaped end, and a layer of electrically conducting material embracing a portion of

both faces of the body, at each side thereof, and the prongs of the fork shaped arms, and forming poles. 65

3. An electric igniter, comprising in combination, a flat insulating body cut out to form a fork shaped end, a layer of electrically conductive material embracing a portion of each flat surface thereof on each side of said body, and the prongs of the fork-shaped end, a wire bridging the prongs of said insulating body and the metal layers on said body, a tube inclosing said insulating body, and means for holding the insulating body in place, substantially as, and for the purpose, set forth. 70

4. An electric igniter, comprising in combination an insulating body having a fork shape at one end, electrically conductive layers on said insulating body, a wire bridging the prongs and conductive layers, a tube inclosing the insulating body, means held in said tube and engaging the said insulating body to hold the same in place, a slowly burning explosive in said tube and in contact with the wire, and a plug of a quick burning explosive in contact with the slow burning explosive and closing the end of 85 the tube. 90

5. The described electric igniter which comprises an insulating body having a fork shape at one end, electrically conductive layers on said insulating body, a wire bridging the prongs and conductive layers of said insulating body, a tube, a body surrounding said insulating body and fitting into said tube, a casting fixing said body surrounding said insulating body in said tube, a slowly burning explosive in said tube and in contact with said wire, and a plug of a quick burning explosive closing the end of said tube, substantially as, and for the purpose, set forth. 95 100

6. An electric igniter, comprising in combination, an insulating body having a hole between its two ends, layers of electrically conducting material on said body, a wire bridging the prongs of said insulating body 110 and the metal layers on said body, a collar piece of about semi-circular section having a tongue adapted to project through the hole in said insulating body and between the conductive layers, and a second collar piece having an opening to receive said tongue, and a tube fitting over said collar pieces and insulating body, substantially as set forth. 115

In testimony whereof I have signed my name to this specification in the presence of 120 two subscribing witnesses.

JOHANN KRANNICHELD.
